Patented May 4, 1915.

UNITED STATES PATENT OFFICE.

WILLIAM E. DAVIS, OF NEW IPSWICH, NEW HAMPSHIRE.

AMUSEMENT DEVICE.

1,138,091.

Specification of Letters Patent.

Patented May 4, 1915.

Application filed February 19, 1915. Serial No. 9,320.

To all whom it may concern:

Be it known that I, WILLIAM E. DAVIS, a citizen of the United States of America, and a resident of New Ipswich, county of 5 Hillsboro, State of New Hampshire, have invented certain new and useful Improvements in Amusement Devices, of which the following is a full and clear specification, reference being had to the accompanying 10 drawings, in which—

Figure 1 is a side elevation and Fig. 2 a vertical longitudinal section of one form of my device; Fig. 3 a horizontal section on the line 3—3 of Fig. 2; and Fig. 4 a 15 vertical longitudinal section of a modified form of the device.

The object of this invention is to provide a simple device for entertaining and amusement purposes, as more fully hereinafter set 20 forth.

In one form of my device, I employ a bottle-like cylinder *a* having an internal chamber *b* and a smaller bore or passage *c* leading from said chamber to the upper end of 25 the cylinder. The chamber *b* is closed at its bottom by means of a plug-like bottom member *d*, through which extends a bore or passage *e* approximately the same in diameter as the bore *c* in axial alignment 30 therewith, said plug being provided with a cone *f* extending upwardly into the chamber *b* and thereby forming an annular channel *g* between it and the wall of the chamber *b*. At intervals around the bottom of the 35 channel *g* are formed window openings *h*, each provided with a bar or stop *i*. A ball *j* is employed, this ball being slightly less in diameter than the passages *c* and *e*, and also less in diameter than the bottom of the 40 channel *g*, so that said ball may pass through the bores *c* and *e* and may also roll around in the bottom of the channel *g* and make its appearance at any one of the windows *h*.

The manner of using this device is as follows: The ball is dropped down through the upper bore *c* and caused to either pass through the entire device by going down through passage *e* or retained in the device by striking against the upper end of the cone 45 and falling into the channel *g*, where it will either appear at one of the windows or will lodge at a point between the same and be invisible, the body of the device being preferably made of opaque material. To cause 50 the ball to pass down through the central passage *e* will require that the device shall be held in an exactly vertical position, since the slightest deviation from the vertical will cause the ball in traversing the enlarged chamber *b* to swerve sufficiently to strike the rim of the cone and thus be deflected away from passage *e*. Tests with this device have shown that it requires but a very slight deviation from the vertical to prevent the ball from going on down through passage *e*, and the shorter the bore *c* the more difficult it is to direct the ball into the passage *e*. 60

To make a game of this device it is simply necessary to give to the central bore *e* and the windows suitable values, say 100 points for the bore and 10, 20, etc., for the windows, the larger amount being given for the bore because of the greater skill required to cause the ball to enter the same. Should the ball 65 lodge at a point between the windows, that may be arranged to count zero. To render it still more difficult to drop the ball through the bore *e*, the bottom of the device may be made slightly convex, as shown, so that the 70 player will have no guide but his own eye to determine whether the device is in a perfectly vertical position when he drops the ball. 75

The above described form of my device is 80 especially intended for use in playing a game. The form of device shown in Fig. 4 is more especially intended for amusement as a puzzle. In this form of the device, both 85 ends of the cylinder are made exactly alike, so as to be indistinguishable from an exterior view, and the windows are omitted. With this device, it will be seen that if the ball be dropped down through the bore *c* it will be very difficult and in fact almost 90 impossible to cause the ball to enter the passage *e*, because of the tendency to leave the vertical in passing through the enlarged chamber, but if the device be inverted and the ball dropped through passage *e*, the 95 ball will to a certainty emerge through the passage *c*, not only by reason of the guidance it receives by passing through the long bore *e*, but also the end of the chamber *b* surrounding the inner end of bore *c* is bevelled to assist in directing it through the bore *c*. It will be seen, therefore, that a player who knows the trick will be able to drop the ball through the device every time and may readily mystify another by handing the device to him in such position that he will naturally insert the ball in bore *c*. 100 105 110

When a player who understands the trick of the device operates it, he can easily, without observance of the other party, invert the device so that the ball will enter the 5 passage *e*. The mystification is increased by the fact that no matter which end of the device one peers into, the two bores *c* and *e* appear to constitute a single uninterrupted bore extending entirely through the device; 10 so that no amount of exterior study of the device will give away the trick. The device is, of course, made of opaque material and care is taken to have both ends of the device alike in appearance.

15 Having thus described by invention, what I claim is:

1. An amusement device consisting of a cylindrical body chambered interiorly, a restricted passage entering each end of the cylinder and arranged in alinement axially, the inner end of one of the passages being sur-

rounded by a cone extending into the interior chamber, and a ball of a diameter adapting it to pass through said passages, for the purpose set forth.

25

2. An amusement device consisting of a cylindrical body chambered interiorly, a restricted passage entering each end of the cylinder and arranged in alinement axially, the inner end of one of the passages being 30 surrounded by a cone extending into the interior chamber, and a ball of a diameter adapting it to pass through said passages, windows being provided at intervals around the cylinder coincident with the bottom of 35 the annular channel formed by said cone.

In testimony whereof I hereunto affix my signature in the presence of two witnesses.

WILLIAM E. DAVIS.

Witnesses:

JOHN F. McCUDDY,
CARRIE LYMAN.
